AUGUST H. SCHNEIDER, OF SYRACUSE, NEW YORK, ASSIGNOR TO CROUSE-HINDS COMPANY, OF SYRACUSE, NEW YORK, A CORPORATION OF NEW YORK.

CONDUIT OUTLET-BOX.

1,327,409.

Specification of Letters Patent.

Patented Jan. 6, 1920.

Application filed February 7, 1916. Serial No. 76,750.

To all whom it may concern:

Be it known that I, AUGUST H. SCHNEIDER, a citizen of the United States, and a resident of Syracuse, in the county of Onondaga and 5 State of New York, have invented a certain new and useful Conduit Outlet-Box, of which the following is a specification.

This invention relates to conduit outlet boxes, and has for its object a conduit outlet 10 box designed to be used in a position where it is exposed to the weather, which box is composed of separable sections, joined together in a particularly simple and efficient manner, so that the joint between the sections 15 is weather tight; and the invention consists in the combinations and constructions hereinafter set forth and claimed.

In describing this invention, reference is had to the accompanying drawings in which 20 like characters designate corresponding parts in all the views.

Figure 1 is an elevation, partly broken away, of one form of my conduit outlet box, the contiguous portion of a conduit being 25 also shown.

Fig. 2 is a longitudinal sectional view of parts seen in Fig. 1.

Fig. 3 is an elevation looking upwardly in Fig. 1, the conduit being removed.

30 Fig. 4 is an inner face view of one of the sections of this conduit outlet box.

Fig. 5 is a detail view of a portion of the means for coupling a conduit to the box.

Fig. 6 is a longitudinal section taken centrally of Fig. 5.

This conduit outlet box comprises, generally, a body open at one side and divided into two sections, the dividing line extending in a plane at an angle to the plane of the 40 open side of the box, the sections being formed with flanges extending the length of the dividing line and terminating at both ends near the open side, the flanges being shaped so that they engage or interlock by 45 movement of one section in a direction parallel to the plane of the dividing line. As here shown, one of the sections is formed with an outwardly extending flange, and the other section is formed with an outwardly 50 extending flange bent around the former flange to form a channel which channel is open at its ends so that the sections may be moved into and out of interlocking engagement by a movement in a direction parallel 55 to the plane containing the dividing line.

1 designates the body of the outlet box which is preferably elongated in form and has an elongated open side or bottom 2 and a dome shaped top 2^a, the body being divided into two sections 3, 4, and the dividing line 5 extending lengthwise of the body in a plane at a right angle to the plane of the open side 2 or the closure 6 for said open side. The lateral sides or ends 7, the greater portions of which are arc-shaped, and the front and rear sides, merge into or form continuations of the top 2^a which is substantially arc-shaped along the dividing line, said line cutting the highest point or ridge of the top so that the surfaces of the top 70 recede from the dividing line.

8 is the outwardly extending flange on one of the sections as the section 3, which flange extends along the line of division 5 and terminates near the lower edge or the open side, 75 and 9 is the flange formed on the section 4, which flange 9 also extends along the line of division 5 and abuts against the flange 8, the flange 9 being bent over the edge of the flange 8 and inwardly at 10 toward the body 80 of the section 3, so that a channel is formed in which the flange 8 is located. The portion 10 of the flange 9 and also the portion extending across the edge of the flange 8 are spaced apart from said flange 8, and the edge 85 of said portion 10 is also spaced apart slightly at 11 from the top of the body 1. The flange 8 terminates at its lower ends in outwardly extending lugs 12, and the flange 9 terminates in housings 13 which inclose the 90 lugs 12. The housings are secured to the lugs by fastening members 14 extending through the walls of the housings 13 and into the lugs 12.

The section 3 is also formed with a laterally extending nipple 15 for connection to a conduit 16 inclosing the service wires. The conduit 16 may be connected to the nipple 15 in any suitable manner, and as here shown it is provided with a nut 17 thereon having 95 laterally extending slotted ears 18, and screws 19 hinged at 20 to laterally extending lugs 21 on the nipple, these screws being movable about their hinges 20 into and out of the open ends of the slots 22, and having 100 nuts and washers 23, 24, at their ends which abut against the outer faces of the ears 18. The nut 17 is formed with an inwardly extending flange 25 which abuts against a suitable washer 26 which in turn abuts against 110

an inwardly extending annular shoulder 27 within the nipple.

In operation the section 4 can be readily detached upon loosening the members 14 and 5 withdrawal upwardly of the section 4, and said section can be replaced in position by the reverse of this movement, the flange 8 moving into the channel formed with the flange 9, when the section 4 is being placed 10 in position.

This conduit outlet box is usually arranged with the conduit 16 in vertical position along the side of the building to which the electric current is to be served, so that 15 the body or head of the box is arranged at an incline, and the device is rendered weather tight by the flanges 8 and 9. Any water beating against the inturned portion 13 of the flange 12 works under the flange 20 9 against the flange 8 where it is free to run downwardly along the receding surface of the flange 8 and out at the lower ends of the channel formed by the flange 9.

What I claim is:

25 1. A conduit outlet box including a body open at one side and divided into two sections, the dividing line between the sections being located in a plane intersecting the plane of the open side and one of the sections being provided with means individual thereto and remote from the dividing line for connection with a conduit, the sections being provided with flanges at their opposing edges along the dividing line and terminating at the open side, one flange being 30 shaped to house the other and the flanges being shaped to interlock by a sliding movement of one of the sections in a direction parallel to the plane of the dividing line, 35 40 substantially as and for the purpose set forth.

2. A conduit outlet box including an elongated body open at one side and divided into two lengthwise sections, the dividing

line of the sections being located in a plane 45 intersecting the plane of the open side and extending lengthwise thereof, one of the sections being provided with a nipple extending laterally from its lengthwise side for connection with an electric conduit, the sections being provided with flanges at their 50 opposing edges, the flange of one of said sections extending outwardly and the flange of the other of said sections including an outwardly extending portion abutting 55 against the former flange and a hooded portion extending over the edge of the former flange and then inwardly onto the outer surface of the section on which the former flange is provided thereby housing the former flange, substantially as and for the purpose described.

3. A conduit outlet box comprising a body open at one side and being divided into two sections, the dividing line extending in a 60 plane at an angle to the plane of the open side, one of the sections being formed with a flange extending along the length of the dividing line and terminating at its ends near said open side, the flange having laterally extending lugs at its ends and the other section having a flange extending along the line of division and having a portion abutting against the former flange and a portion 65 extending over the edge of the former flange 70 and inwardly toward the outer face of the body, the latter flange forming a channel for receiving the former flange and the latter flange widening at its ends and forming 75 housings inclosing said lugs, and fastening 80 means extending through a wall of the housings and into the lugs, substantially as and for the purpose described.

In testimony whereof, I have hereunto signed my name, at Syracuse, in the county 85 of Onondaga, and State of New York, this 10th day of September, 1915.

AUGUST H. SCHNEIDER.
